UNITED STATES PATENT OFFICE.

CHARLES T. AMMON, OF WOOSTER, OHIO, ASSIGNOR OF ONE-HALF TO SAMUEL KREADY, OF WOOSTER, OHIO.

STEAM HEATING SYSTEM.

No. 904,499.

Specification of Letters Patent.

Patented Nov. 24, 1908.

Application filed January 28, 1908. Serial No. 413,020.

To all whom it may concern:

Be it known that I, CHARLES T. AMMON, citizen of the United States, residing at Wooster, in the county of Wayne and State 5 of Ohio, have invented certain new and useful Improvements in Steam Heating Systems, of which the following is a specification.

This invention contemplates certain new 10 and useful improvements in steam heating apparatus and the object of the invention is an improved device that is designed to be applied to the boiler and the return pipe of such an apparatus to prevent the water in 15 the boiler from backing up in the returning pipe which, as is well known, is a most objectionable feature in the ordinary heating systems of this character.

With this and other objects in view that 20 will more fully appear as the description proceeds, the invention consists in certain constructions and arrangements of parts that I shall hereinafter fully describe and claim.

25 For a full understanding of the invention and the merits thereof, reference is to be had to the following description and the accompanying drawing, in which:

Figure 1 is a perspective view of my improved device showing it applied to a steam heating apparatus; and, Fig. 2 is a view in elevation thereof with parts in section.

Corresponding and like parts are referred to in the following description and indicated in all the views of the drawing by the same reference characters.

Referring to the drawing, A designates a boiler to which my invention is applied, which is heated by any suitable means (not 40 shown) and which is of any desired construction or design, filled with water to a predetermined point and provided above the water with a steam space B. A main supply pipe C leads from the steam space B to 45 the radiating pipes (not shown), and a return pipe D communicates with the radiating pipes for the purpose of conducting the water condensed therein to the boiler, the end of the pipe D being connected to the 50 latter near the bottom thereof.

The return pipe D extends upwardly from 55 its lower end in a substantially vertical position to a point preferably below the level of the water in the boiler and forms a stand-

a steam chest 2 that extends above the water level as shown. The water in the boiler obviously fills the stand-pipe and the lower portion of the steam chest, and steam is admitted to the upper portion of the chest by 60 means of a steam pipe 3 connecting the chest with the steam space B of the boiler. The steam in the upper portion of the chest manifestly exerts its pressure on the water in the lower portion thereof to effectually 65 prevent such water from backing up in the return pipe system, although said steam does not interfere with the returning of the condensed water to the boiler.

In order to prevent the steam admitted to 70 the chest, from circulating through the return pipe, the latter is provided with a U-shaped trap 4 the ends of which extend above the water level as shown, one end of the trap being shorter than the other and 75 being connected to the upper portion of the steam chest by an elbow 5. This trap 4 is filled with water and forms an effectual seal.

In the practical use of my improved device, the condensed water is led by the return 80 pipe into the taller end of the trap, and is discharged therefrom by gravity into the chest and is thence conducted through the stand-pipe to the boiler.

In the preferred construction of the device 85 a drain-cock 6 is secured to the lower portion or bend of the trap to provide means for drawing off the water in case the latter should become polluted with sediment, and a vent-cock 7 is provided at the taller end of 90 the trap to form an escape opening for the air forced through the pipes by the steam when the latter is first admitted thereto.

Having thus described the invention, what I claim is:

1. In a heating system, the combination with the boiler and return pipe, of a stand-pipe connected to the boiler below the water level, a steam chest connected to the stand-pipe and extending above and below the 100 water level in the boiler, the water in said boiler filling the stand-pipe and partially filling the steam chest in alignment with the water level in the boiler, the return pipe being in continuous communication with the 105 steam chest above the water level therein, and a steam pipe leading from the boiler to the upper portion of the steam chest, and admitting steam to the latter so as to exert a continual pressure upon the water in the 110

steam chest equal to the pressure upon the water in the boiler.

2. In a heating system, the combination with the boiler and return pipe, of a stand-pipe connected to the boiler below the water level, a steam chest connected to the stand-pipe and extending above and below the water level in the boiler, the water in said boiler filling the stand-pipe and partially filling the steam chest in alinement with the water level in the boiler, the return pipe being in continuous communication with the steam chest above the water level therein, a steam pipe leading from the boiler to the

upper portion of the steam chest and admitting steam to the latter so as to exert a continual pressure upon the water in the steam chest equal to the pressure upon the water in the boiler, and means for preventing the circulation of the steam admitted to the steam chest through the return pipe.

In testimony whereof I affix my signature in presence of two witnesses.

CHARLES T. AMMON. [L.S.]
